(57) **CLAIM**

The ornamental design for a gasket, as shown and described.

DESCRIPTION

FIG. 1 illustrates a front elevational view of a gasket showing our new design;

FIG. 2 illustrates a top plan view thereof;

FIG. 3 illustrates a side elevational view thereof;

FIG. 4 illustrates a cross-sectional view of the gasket taken along line 4-4 in FIG. 3;

FIG. 5 illustrates a front perspective view thereof;

FIG. 6 illustrates a cross-sectional environmental view of the gasket of FIG. 1 in use; and,

FIG. 7 illustrates another cross-sectional environmental view of the gasket of FIG. 1 in use.

The broken lines in the drawings illustrate environment that
forms no part of the claimed design.

1 Claim, 7 Drawing Sheets
